Primary Examiner — Mary Ann Calabrese*Assistant Examiner* — Katelin G Kloberg(74) *Attorney, Agent, or Firm* — Suzanne Kikel(57) **CLAIM**

The ornamental design for a healing jacket for dogs, as shown and described.

DESCRIPTION

FIG. 1 is a perspective view of a healing jacket for dogs, showing my new design within an environment of use; FIG. 2 is a top perspective view of the healing jacket for dogs, shown in a flat position; FIG. 3 is a bottom perspective view thereof; FIG. 4 is an exploded bottom perspective view, shown with the pocket in an open configuration; FIG. 5 is another bottom perspective view, shown with the pockets in an alternate configuration; FIG. 6 is a top plan view of the article as shown in FIG. 2; FIG. 7 is a bottom plan view thereof; FIG. 8 is a right side elevation view thereof; FIG. 9 is a left side elevation view thereof; FIG. 10 is a front elevation view thereof; and, FIG. 11 is a rear elevation view thereof. The broken lines depicting a dog in FIG. 1 are showing environmental subject matter that forms no part of the claimed design.
